United States Patent Office.

CHARLES PERKES, OF PHILADELPHIA, PENNSYLVANIA.

Letters Patent No. 96,033, dated October 19, 1869.

IMPROVEMENT IN COMPRESSION-COCKS.

The Schedule referred to in these Letters Patent and making part of the same.

To all whom it may concern:

Be it known that I, CHARLES PERKES, of the city of Philadelphia, and State of Pennsylvania, have invented a certain new and useful Improvement in Stops, or Valves for Controlling the Flow of Fluids in Tubes; and I do hereby declare the following to be a full, clear, and exact description thereof, reference being had to the accompanying drawings, and the letters of reference marked thereon.

The nature of my invention consists in so forming and applying the valve and the seat that they remain automatically in proper repair and adjustment, and are not subjected to the wear and destruction incident to other stop-valves or cocks.

The precise construction and character of my improvement will fully appear in the following description and drawings annexed.

The same letters of reference apply to the same parts in the several figures.

Figure 1 shows a side elevation.

Figure 2 shows a vertical section.

Figures 3, 4, 5, and 6, show the parts in detail.

The several figures show the application of this invention to water-faucets or hydrants.

A represents a valve-seat.

B represents the valve, which is made of any elastic material, vulcanized rubber being found the most convenient. This valve B is made spherical, and when open is free to float and rotate in the current of fluid passing through the cock in the direction of the arrows in fig. 2.

The seat A is not spherical, but is formed so as to be a zone of an oblate spheroid.

The cup C is depressed by the screw D, retained by the collar E formed upon it, and confined by the cap

F, working in the nut G, formed on the upper portion of the cup C, when the valve B is compressed into a spheroidal form, and fits to the cup C and valve-seat A, and, by being rotated by the current, is presented in all directions to the compressing action of the screw and nut; but in no case does it become permanently changed from its spherical form when relieved of the pressure by the cup C.

Another advantage is obtained by the spheroidal form of seat and cup, in combination with a loose elastic ball. It is, that any foreign matter between the valve and seat is readily drawn by the current from between them, by reason of the diverging form of the space in relation to the direction of the current.

I am aware that elastic balls free to rotate in currents have been used as self-acting valves for pumps; also, that valves having elastic packings have been used with seats corresponding in form with the form of the valve when not compressed; and, also, that valves formed of an elastic sphere have been used with a seat of metal of corresponding form, into which they have been forced and expanded, by screw or other convex form pressing in the side of the sphere opposite to the opening which the valve is intended to close. All of these, therefore, I distinctly disclaim; but

What I claim as my invention, and desire to secure as such by Letters Patent, is—

The combination of the spherical elastic loose-ball valve with the oblate-spheroidal seat and oblate-spheroidal compressing-cup, substantially as described.

CHARLES PERKES.
